US00D457908S

(12) **United States Design Patent** (10) Patent No.: **US D457,908 S**
 Lane et al. (45) Date of Patent: ** May 28, 2002

(54) **EYESHIELDS**

(75) Inventors: **Henry Welling Lane, Ronald L. Underwood**, both of San Luis Obispo, CA (US)

(73) Assignee: **Dioptrics Medical Products, Inc.**, San Luis Obispo, CA (US)

(**) Term: **14 Years**

(21) Appl. No.: **29/130,173**

(22) Filed: **Sep. 27, 2000**

(51) LOC (7) Cl. **16-06**

(52) U.S. Cl. **D16/312**

(58) Field of Search D16/101, 300-330; D29/109, 110; 351/41, 44, 51, 52, 158, 156, 157; D2/865, 866, 891, 894; 2/10, 12-13, 426-430, 432, 436, 447

Primary Examiner—Raphael Barkai

(74) Attorney, Agent, or Firm—Haverstock & Owens LLP

(57) **CLAIM**

We claim the ornamental design for eyeshields, as shown and described.

DESCRIPTION

FIG. 1 is a front elevation view of eyeshields showing of our new design;

FIG. 2 is a rear elevation view of eyeshields thereof;

FIG. 3 is a bottom view of the eyeshields thereof;

FIG. 4 is a top view of the eyeshields thereof;

FIG. 5 is a side view of the eyeshields thereof;

FIG. 6 is a side view of the opposite side shown in FIG. 5 of the eyeshields thereof;

FIG. 7 is a bottom perspective view of the eyeshields thereof;

FIG. 8 is a side perspective view of the eyeshields thereof;

FIG. 9 is a side perspective view of the eyeshields thereof; and,

FIG. 10 is a front perspective view of the eyeshields thereof.
